(57) **CLAIM**

The ornamental design for an autonomous driver assistance device, as shown and described.

DESCRIPTION

FIG. 1 is a front perspective view of a first embodiment of an autonomous driver assistance device;

FIG. 2 is a front view of the first embodiment of the autonomous driver assistance device;

FIG. 3 is a back view of the first embodiment of the autonomous driver assistance device;

FIG. 4 is a left view of the first embodiment of the autonomous driver assistance device;

FIG. 5 is a right view of the first embodiment of the autonomous driver assistance device;

FIG. 6 is a top view of the first embodiment of the autonomous driver assistance device;

FIG. 7 is a bottom view of the first embodiment of the autonomous driver assistance device;

FIG. 8 is a front perspective view of a second embodiment of the autonomous driver assistance device;

FIG. 9 is a front view of the second embodiment of the autonomous driver assistance device;

FIG. 10 is a back view of the second embodiment of the autonomous driver assistance device;

FIG. 11 is a left view of the second embodiment of the autonomous driver assistance device;

FIG. 12 is a right view of the second embodiment of the autonomous driver assistance device;

FIG. 13 is a top view of the second embodiment of the autonomous driver assistance device; and,

FIG. 14 is a bottom view of the second embodiment of the autonomous driver assistance device.
